United States Patent Office

Des. 219,484
Patented Dec. 15, 1970

219,484

BOAT WITH TRANSPARENCIES IN A PORTION OF THE BOTTOM THEREOF

Homer L. Lott, 7131 SW. 5 Terrace 33144, and Edgar R. Lewis, Jr., 3193 NW. 20th St. 33147, both of Miami, Fla.

Filed Apr. 25, 1969, Ser. No. 16,897

Term of patent 14 years

Int. Cl. D12—06

U.S. Cl. D71—1

FIG. 1

FIG. 2

FIG. 1 is a top plan view of a new boat with transparencies in a portion of the bottom thereof, showing our new design.

FIG. 2 is a side elevation thereof.

FIG. 3 is a front elevational view thereof.

FIG. 4 is a rear elevational view thereof.

FIG. 5 is a bottom plan elevational view thereof.

We claim:

The ornamental design for a boat with transparencies in a portion of the bottom thereof, as shown.
